UNITED STATES PATENT OFFICE.

JAMES EDWARD BARNABY, OF GARNETT, KANSAS.

RAILWAY-CROSSING SIGNAL.

Application filed October 18, 1924. Serial No. 744,427.

The object of this invention is to minimize the casualties incident to traffic at the intersection of public roads with railways and provides a signal adapted to be automatically operated by a train approaching the crossing so as to give ample warning to pedestrians and drivers of vehicles and thereby avoid an accident.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the specification,

Figure 1 is a top plan view of the intersection of a public road and railway provided with signaling means embodying the invention,

Figure 2 is a front view of the signal showing the parts on a larger scale, and partly in section,

Figure 3 is a top plan view of the parts illustrated in Figure 2,

Figure 4 is a side view of the signal,

Figure 5 is a fragmentary view of a portion of the cross piece and the attached housing and guides for the movable signal, and

Figure 6 is a diagrammatic view showing the operating circuit.

Corresponding and like parts are referred to in the following description and designated in the several views of the drawings by like reference characters.

The numeral 10 denotes the crossing of a public road 11 and railway 12 and in accordance with the present invention, the signal is located along the roadway at any determinate distance from the crossing and

as shown comprises a supporting frame, a warning member and operating means therefor. The supporting frame comprises uprights 13 and 14 and a cross piece 15 although it is to be understood that it may

be of any desired construction according to conditions met with. The upright 14 is preferably hollow to enclose the operating parts. A housing 16 is pendant from the cross piece 15 and is provided upon opposite sides with suitable warning legends such

as "Look out for the cars". A warning member 17 is normally protected by the housing 16 and is mounted for vertical movement to be lowered upon the approach of a train and this warning member may be painted red and contain suitable words such as "Stop" to warn a driver or pedestrian of the approach of a train. Chains 18 or other warning elements are attached to the warning member 17 and move therewith. A cable 19 or other flexible connection is attached at one end to the warning member 17 and is connected at its opposite end to a drum 20 and when wound upon the drum holds the member 17 elevated as indicated most clearly in Figure 2. A weighted cable 21 or analogous flexible connection is attached to the drum 20 and is wound thereon as the cable 19 is unwound therefrom and the purpose of this weighted cable 21 is to elevate and hold the warning member 17 in normal position, that is, within the housing 16. Guide pulleys 22 applied to the cross piece 15 give proper direction to the flexible connection 19. The warning member 17 is held for vertical movement into and out of the housing 16 by means of a frame 23 formed preferably of a rod bent into U-shape, as shown in Figures 2 and 5. The upper terminals of the rod form guide members 23^a that cooperate with guide elements 24 having loops 24^a receiving said members 23^a. At the lower ends of the guide members 23^a frame 23 is enlarged to receive warning member 17, said enlargement including inturned portions 23^b at the lower ends of members 23^a, side members 23^c engaging the sides of the warning member 17, and a connection member 23^d.

An electric motor 25 is preferably disposed within the lower portion of the upright 14 and its shaft is connected by means of a drive belt 26 with the drum 20 and in the preferable construction the drive belt 26 consists of a sprocket chain cooperating with sprocket wheels applied to the shaft of the motor and drum. The motor 25 is included in an electric circuit 27 which also includes rail sections 28 which are electrically insulated, the circuit being closed when the train reaches the block containing the rail sections 28 as indicated at 29 in the diagram in Figure 6 and when the circuit is closed the motor 25 is actuated and operates the drum 20 to unwind the cable 19 there-

from and wind the cable 21 thereon and during this operation the warning member 17 is lowered into position to warn a pedestrian or driver of a vehicle not to pass over the crossing 10 because of the approach of a train. After the train has passed the crossing the motor circuit is broken and the weight attached to the cable 21 comes into play to rotate the drum 20 in a reverse direction thereby winding the cable 19 thereon and elevating the warning member 17 into normal position, which as stated is shown by the full lines in Figure 2.

What is claimed is:—

15 An apparatus of the class described, com-

prising a warning member, a generally U-shaped rod disposed about the member, said rod providing spaced guiding terminals, and the rod having inturned portions at the lower end of the guiding terminals whereby the 20 warning member is held against displacement longitudinally of the rod, a supporting member to which said terminal portions are guided, guide members for said terminals extending above said supporting member, a 25 housing for said warning member depending from the supporting member, and means to raise and lower said warning members.

In testimony whereof I affix my signature.
JAMES EDWARD BARNABY.
